Goldstein & Fox P.L.L.C.(57) **CLAIM**

The ornamental design for a tire, as shown and described.

DESCRIPTION

FIG. 1 is a front perspective view of a tire showing the claimed design;

FIG. 2 is a front view thereof, the rear view being the same;
FIG. 3 is a top plan view thereof, the bottom plan view being the same;

FIG. 4 is a right side view thereof, the left side view being the same;

FIG. 5 is an enlarged view taken along line 5-5 in FIG. 1;
FIG. 6 is an enlarged view of the portion 6-6 in FIG. 2; and,
FIG. 7 is a cross-sectional view taken along line 7-7 in FIG. 6.

In the drawings, the broken lines show portions of the tire that form no part of the claimed design.
